(57) **CLAIM**

The ornamental design for a self-sealing valve for an inflatable body, as shown and described.

DESCRIPTION

FIG. 1 is a front isometric view of the self-sealing valve of the present invention;

FIG. 2 is a front view thereof;

FIG. 3 is a top view thereof;

FIG. 4 is a right-side view thereof;

FIG. 5 is a rear view thereof, symmetrical to said front view;

FIG. 6 is a bottom view thereof; and,

FIG. 7 is a left view thereof, symmetrical to said right-side view.

The broken lines shown in the drawings are for the purpose of illustrating portions of the self-sealing valve for an inflatable body and form no part of the claimed design.
